UNITED STATES PATENT OFFICE.

JOHN H. LEGE, OF SAN ANTONIO, TEXAS.

CHIROPRACTIC TABLE.

1,395,646.

Specification of Letters Patent.

Patented Nov. 1, 1921.

Application filed May 7, 1921. Serial No. 467,552.

To all whom it may concern:

Be it known that I, JOHN H. LEGE, a citizen of the United States, residing at San Antonio, in the county of Bexar and State 5 of Texas, have invented new and useful Improvements in Chiropractic Tables, of which the following is a specification.

This invention relates to surgical appliances, particularly to tables used by chiropractors in their manipulations of the human body, and has for its object the provision of a table or attachment to a table including simultaneously movable head and abdomen supports. In adjusting the spinal 15 vertebrae it is necessary to flex the spine anteriorly in order to widen the spaces between the vertebrae as much as possible anteriorly in order to secure an adjustment of the greatest benefit. In certain well known 20 types of tables there is provided a head rest which is stationary while the abdomen support is movable. The disadvantage of such structure is that when the abdomen support is lowered only the lower portion of the 25 spine is properly flexed leaving the upper portion flexed in the opposite direction which results in giving a compound curve to the spine.

It is with the above facts in view that 30 the present invention has been designed which embodies a head rest, chest support and abdomen support all mounted upon a single hinged member which will automatically adjust itself to the patient lying upon 35 the table, spring means being provided for opposing the movement.

An additional object is the provision of a device of this character which will be simple and inexpensive in construction, highly efficient in use, durable and safe in use, and a general improvement in the art.

With the above and other objects and advantages in view, the invention consists in the details of construction to be herein- 45 after more fully described and claimed and illustrated in the accompanying drawings in which—

Figure 1 is a side elevation of a table equipped with my device showing it in initial or normal position,

Fig. 2 is a plan view;

Fig. 3 is a longitudinal sectional view showing the parts moved into the position that it will assume when a patient is upon the table,

Fig. 4 is a cross sectional view on the line 4—4 of Fig. 1, and

Fig. 5 is a cross sectional view on the line 5—5 of Fig. 1.

Referring more particularly to the drawings, I have shown a table, known to the profession as the Griffin table, which I have equipped with my improvement. This table comprises a frame 10 carrying a main stationary leg support 11 with which is slidably 60 associated an auxiliary leg support 12 adapted to be extended from beneath the support 11 for holding up pads 13. At its opposite end the frame includes four upright posts 14 and 15 which in tables of this type, are 70 for the purpose of carrying a rigid head support. Extending across the frame is a board or other member 16 upon which is hinged, as shown at 17, an inclined board 18 upon the free edge of which is hinged, 75 as shown at 19, a second oppositely inclined board 20. In tables of this type there is provided an abdominal support fixed upon a longitudinal bar or board which is pivoted at the upper ends of the posts 14 and which 80 is connected with the free edge of the board 20 by hinges. Connected with the board 20 is a plurality of springs 21 which are connected with a pivoted lever 22 carrying a pawl member 23 coöoperating with a species 85 of ratchet bar 24 whereby the tension of the springs may be varied according to the weight of the patient lying upon the table.

In the ordinary structure above outlined, the abdominal support is the only movable member, aside from the extensible auxiliary leg support. The great drawback or disadvantage of such an arrangement is that the head rest is stationary regardless of the degree of movement of the abdominal support. In 95 adjusting the spinal vertebrae it is necessary to flex the spine anteriorly only in order to widen the spaces between the anterior margins and this is impossible in the use of the ordinary type of table.

In carrying out my improvement on the above described well known structure I em-

ploy a longitudinal board 25 which is connected with the free edge of the board 20 by hinges 26, and which is hinged, as shown at 27, to a cross piece 28 connecting the 5 posts 15. Secured upon one end of this board 25 is an abdominal support 29, mounted intermediate the ends is a small chest support 30, and carried by the other end is a head support 31 including an inclined 10 frame 32 equipped with spaced pads 33. The upper ends of the posts 14 and 15 are cut away, as shown at 34, for the accommodation of the frame 32 whereby to form stops for limiting downward movement of 15 the head rest under the influence of the springs 21. I also provide springs 35 connected with the head end of the board 25 and with a cross member 36 of the frame, these springs operating in conjunction with 20 the springs 21.

In some instances, or at certain times, as for instance when a patient first takes his place upon the table, it is highly desirable to hold all the supports rigid. In order to 25 accomplish this I provide a latch device which comprises a short bar 37 hinged upon the underside of the board 24, as shown at 38, and having its free end engageable within a recess 39 in a cross piece 40 carried 30 by the frame, such engagement preventing swinging of the board 25.

In order to release this latch conveniently I provide a rod 41 journaled in guides 42 on the underside of the board 25 and formed 35 at one end with an arm 43 connected with a link 44 which is in turn pivotally connected with the bar 37, as shown at 45. At its other end the rod 41 is formed with an inclined handle portion 46 whereby it may be rocked 40 to lift the bar 37 out of engagement within the recess 39 to permit swinging of the board 25 and the supports carried thereby. I also provide a catch 47 engageable by the 45 handle 46 whereby to hold the bar 37 in elevated or unlatched position.

From the above description and a study of the drawings it is believed that the construction and operation will be fully understood without further detailed explanation. 50 My device is shown as being built into a table of more or less conventional form, a specific type being illustrated, but it will be noted that my movable element might readily be associated with tables of other 55 types and might be built into any new type of table if such be desired.

While I have shown and described the preferred embodiment of my invention, it is of course to be understood that I reserve the 60 right to make such changes in the form, construction and arrangement of parts as will not depart from the spirit of the invention or the scope of the subjoined claims.

Having thus described my invention, I 65 claim:

1. In a chiropractic table including a frame, a stationary leg support carried thereby, and an upright frame at the end of the frame opposite the leg support; an elongated supporting bar hinged intermediate its ends 70 upon said upright frame, spring means opposing movement of said hinged bar, a head rest carried by the forward end of said bar, a chest support on the intermediate portion of said bar, and an abdomen support 75 upon the rear end of said bar.

2. In a chiropractic table including a frame, a stationary leg support carried thereby, and an upright frame at the end of the frame opposite the leg support; an elongated 80 supporting bar hinged intermediate its ends upon said upright frame, spring means opposing movement of said hinged bar, a head rest carried by the forward end of said bar, a chest support on the intermediate portion 85 of said bar, and an abdomen support upon the rear end of said bar, and releasable catch means for locking said bar against movement.

3. A chiropractic table comprising a frame, a stationary leg support at one end thereof, a slidable auxiliary leg support disposed beneath said first named leg support, a transverse inclined board hingedly mounted upon said frame, an oppositely inclined board 90 hinged upon the free edge of said first named inclined board, adjustable spring tension connected with said first named board, an upright frame at the opposite end of said main frame, an elongated bar hinged intermediate its ends upon said upright frame and having its rear end hingedly connected with the free edge of said second named inclined board, a head support upon the forward end of said bar, a chest support upon the intermediate portion of said bar, an abdomen support on the rear end of said bar, and a plurality of springs connected with the forward end of the bar coöperating with 95 said first named springs to oppose movement 100 of the bar.

4. A chiropractic table comprising a frame, a stationary leg support at one end thereof, a slidable auxiliary leg support disposed beneath said first named leg support, a transverse inclined board hingedly mounted upon said frame, an oppositely inclined board 115 hinged upon the free edge of said first named inclined support, adjustable spring tension connected with said first named board, an upright frame at the opposite end of said main frame, an elongated bar hinged intermediate its ends upon said upright frame and having its rear end hingedly connected with the free edge of said second named inclined board, a head support upon the forward end of said bar, a chest support upon the intermediate portion of said bar, an abdomen support on the rear end of said bar, a plurality of springs connected with the 120 125 130 forward end of the bar coöperating with said first named springs to oppose movement of the bar.

forward end of the bar coöperating with said first named springs to oppose movement of the bar, a transverse member carried by the main frame and formed with a notch, a bar pivoted upon the underside of the first named bar and engageable within said notch for locking the first named bar against movement, and means for moving and holding said locking bar out of engagement with said notch. In testimony whereof I hereto affix my signature. 10

J. H. LEGE.
